UNITED STATES PATENT OFFICE.

GEORGE M. BOWEN, OF BROOKLYN, NEW YORK.

ODORLESS GARBAGE-CAN COVER

1,121,161.

Specification of Letters Patent. Patented Dec. 15, 1914.

Application filed May 13, 1914. Serial No. 838,335.

To all whom it may concern:

Be it known that I, GEORGE M. BOWEN, a citizen of the United States, residing at Brooklyn, in the county of Kings, State of New York, have invented certain new and useful Improvements in Odorless Garbage-Can Covers; and I do hereby declare the following to be a full, clear, and exact description of the invention, such as will enable others skilled in the art to which it appertains to make and use the same.

This invention relates to receptacles, particularly to receptacles for containing refuse such as garbage and the like, and has for its object the provision of a novel cover for a receptacle of this character which is so constructed as to prevent the escape of any obnoxious gases or odors from the receptacle caused by the fermentation of the contents.

An important object is to provide a device of this character which may be readily attached to any well known or preferred type of garbage receptacle in common use without in any way changing the structure.

More specifically the object of the invention is the provision of a cover provided with interior mechanism whereby access to the garbage container is prevented while the cover is itself in open position, this interior mechanism being shiftable to discharge into the container the matter deposited within the cover, said shifting being incapable of accomplishment until the cover is in its closed position.

Another object is the provision of a device of this character which will be simple and efficient in operation, inexpensive in manufacture, durable in service and a general improvement of the art.

With these and other objects and advantages in view, my invention consists in the novel construction and arrangement of parts as will be hereinafter more fully described and claimed, and illustrated in the accompanying drawings, in which—

Figure 1 is a top plan view of my device, Fig. 2 is a vertical sectional view therethrough showing the device applied to a garbage receptacle, showing it in its open position, Fig. 3 is a cross sectional therethrough, and Fig. 4 is a vertical sectional view through the device with the revoluble plate swung half way.

Referring more particularly to the drawings, the numeral 5 designates a garbage receptacle of any well known or preferred

type such as the cylindrical galvanized container in popular use.

My invention is adapted to be disposed upon the open end of the container 5 and comprises a preferably frusto-conical shell 6 provided with a bottom 7 extending only slightly more than half way across to leave an open space 8. The bottom 7 is spaced somewhat above the extreme lower edge of the casing 6 to provide an annular flange 9 which is adapted to be disposed exteriorly of the container 5 for preventing the casing 6 from displacement thereon.

At its upper end the casing 6 is provided with a plate 10 soldered or otherwise secured thereon and disposed exactly above and in alignment with the space 3 in the bottom of the casing. This leaves a space 11 in the top of the casing immediately above the bottom plate 7.

A closure plate 12 is hingedly secured as at 13 upon the edge of the top plate 10 and is provided with a flange 14 adapted to embrace the upper end of the casing 6.

Revolubly mounted within the casing 6 is a plate 15 which is bent centrally to form a semi-cylindrical recess 16 adapted to cooperate with similarly bent brace arms 17 extending across and suitably secured upon the plate 15.

A spindle 18 is disposed between the bent portions of the plate 15 and the arms 17 and is secured therein by rivets or other suitable fastening devices, though in the present instance screws and nuts 19 and 20 are shown. The spindle 18 is journaled through the bottom plate 7 and also extends through the top plate 10, being provided upon its extreme upper end with an operating handle 21 by means of which the plate 15 may be rotated.

The operation of the device is as follows: The handle 21 being in the position shown in Fig. 1, that is, parallel with the edge of the top plate 10, the plate 15 is parallel with the edge of the bottom plate 7 and therefore cuts off and prevents the passage of any gases or odors from the garbage container 5 into the device. When the handle is in this position the closure plate 12 may be lifted so that refuse may be deposited through the opening 11 and on to the bottom plate 7. The closure plate 12 is then swung down and the handle 21 turned so that the plate 15 in its rotary movement will sweep the refuse from the plate 7 into the space 8 and conse-

quently into the receptacle 5. The handle 21 should be rotated through an arc of 180 degrees whereupon it will return into a position parallel with the edge of the plate 10.
5 Unless the handle 21 is in such parallel position it will be obvious that the closure plate 12 cannot be opened. Furthermore the handle 21 cannot be rotated unless the plate 12 is closed. It will therefore be apparent that
10 when the plate 12 is raised the escape of gases or odors is prevented by the plate 15 and when the plate 15 is moved so that gases or odors might escape into the casing 6 they cannot escape therefrom as the opening 11 is
15 then necessarily closed by the engagement of the plate 12 with the handle 21.

From the foregoing description and a study of the drawings it will be apparent that I have thus provided a refuse receptacle cover which will readily permit of the deposit of refuse therein and at the same time prevent the escape of gases or odors.

It will be readily understood that I may make various changes in the form, construction, arrangement and combination of parts without departing from the spirit of the invention or limiting the scope of the subjoined claims.

Having thus described my invention, I claim:

1. In combination with a refuse receptacle, a cover member comprising a casing, a plate extending partly across the bottom of said casing, a second plate extending partly across the top of said casing and in opposite relation to said first named plate, a closure plate hingedly connected with said second named plate, a plate journaled through said first and second named plates

and revoluble within said casing, and a handle connected with said revoluble plate and extending through said second named plate, said closure plate being openable when said revoluble plate is disposed parallel with the edge of said first named plate. 40
45

2. In combination with a refuse receptacle, a cover member comprising a casing provided upon its top and bottom with openings in staggered relation to each other, a closure plate adapted to close said upper opening, a plate revoluble within said casing and adapted to divide said casing into two compartments, communicating normally with said openings and a handle connected with said revoluble plate and 50 adapted to engage said closure plate when said revoluble plate extends wholly or partly across said lowermost opening. 55

3. In combination with a refuse receptacle, a cover member comprising a casing 60 provided upon its top and bottom with openings, the bottom opening communicating with the interior of said receptacle, a hinged closure plate for closing the opening in the top, and means for preventing 65 communication of said openings with each other, said means being revoluble to establish communication between said openings when said closure plate is closed, said revoluble plate being incapable of movement 70 when said cover plate is open.

In testimony whereof, I affix my signature, in the presence of two witnesses.

GEORGE M. BOWEN.
